ENVELOPE MAKING MACHINE

Abraham Novick, Flushing, N. Y., assignor to
 F. L. Smithe Machine Co., Inc., New York, N. Y.,
 a corporation of New York

Application October 2, 1931, Serial No. 566,461

9 Claims. (Cl. 93—62)

This invention relates to envelope making machinery, and has for an object to provide a machine for making open end envelopes in a novel and efficient manner.

5 In accordance with one feature of the invention, the order of treatment of the envelope blanks involves first gumming, folding and adhesively uniting the side flaps, then gumming and drying the sealing flaps, and finally gumming the bottom flaps and folding the bottom and sealing flaps over against the envelope body.

In accordance with a further important feature of the invention, provision is made of an endless drying conveyor on which the envelope blanks are deposited with their gummed faces turned toward the conveyor. The blanks are retained on the conveyor throughout substantially the entire orbit of travel thereof, that is, throughout the outgoing and return stretches, 20 and provision is made between the stretches of the conveyor of means for blowing air against the gummed faces of the blanks.

Other objects and advantages will hereinafter appear.

25 In the drawings forming part of this specification:

Figure 1 is a diagrammatic, side elevation of the introductory end of the machine, a portion of the drying conveyor being shown, also;

30 Figure 2 is a fragmentary, diagrammatic, plan view of a portion of the mechanism illustrated in Figure 1;

Figure 3 is a similar view of another portion of the mechanism illustrated in Figure 1;

35 Figure 4 is a view similar to Figure 1, illustrating a portion of the machine adjoining that of Figure 1;

Figure 5 is a diagrammatic, plan view, partly broken away, illustrating the mechanism of Figure 4;

40 Figure 6 is a side elevation, similar to Figures 1 and 4, and illustrating a portion of the machine adjoining that of Figure 4;

Figure 7 is a diagrammatic, plan view of a portion of the mechanism illustrated in Figure 6;

45 Figure 8 is a fragmentary, enlarged, detail view in side elevation illustrating the gripper construction and mounting;

Figure 9 is a plan view on the same scale as Figure 8, illustrating the mechanism disclosed in Figure 8;

50 Figure 10 is a view in side elevation showing a portion of the machine which adjoins that of Figure 6;

Figure 11 is a diagrammatic, plan view illus-

trating portions of the mechanism shown in Figure 10;

5 Figure 12 is a view in side elevation illustrating a portion of the machine adjoining that of Figure 10;

Figure 13 is a diagrammatic, plan view illustrating a portion of the mechanism shown in Figure 12.

If Figures 1, 4, 6, 10 and 12 are laid end to end in the order named at the lines A, A, B, B, C, C 10 and D, D, the machine is seen in its entirety in side elevation, with the exception that a portion of the receiving conveyor for finished envelopes, shown at the right hand end of Figure 12, is broken away.

15 In Figure 1 disclosure is made of a feeder of the type disclosed in Letters Patent of the United States No. 1,385,468, granted to Charles F. Pflanze on July 26, 1921. This feeder comprises a cylinder 1 having friction blocks 2 set therein and effective at each revolution of the cylinder to take the topmost blank off of a stack of blanks situated on a shelf 3, a rubber shoe 2a being effective to prevent the feed of more than one sheet at a time. The blanks are delivered by the cylinder 1 in conjunction with an auxiliary feed

20 roll 4 to a conveyor 5 which travels fast enough to maintain the blanks in spaced out relation. The conveyor 5 includes a pair of endless chains 6 which run upon sprockets 7, 8 and 9. Each of the chains 6 carries pusher fingers 10 for engaging in the angles formed at the junctions of the sealing flaps 11 and side flaps 12 and 13 of the envelope blanks B for aligning the blanks and positively feeding them forward. The cylinder 1 is so timed with relation to the conveyor

25 5 that the blanks B arrive in position to be engaged by the fingers 10 a little before the fingers 10 come into position to engage them. It is intended that the blanks B remain idle in such 30 position until overtaken by the fingers, but should a blank be carried forward prematurely or be skewed or misplaced for any other reason, it will 35 be set back against the fingers as it travels along the upper stretch of the conveyor 5. For this purpose provision is made of fixedly mounted 40 spring fingers 14 and 15 which engage the upper surfaces of the blanks to press them against a suitable table, not shown, and thus exert a frictional drag upon them.

45 The conveyor 5 delivers the blanks across a table 16 to a feeding couple comprising rolls 17 and 18, and this couple in turn delivers the blanks across a table 19 to scoring means comprising a cylinder 20 and scoring wheels 21 for

providing longitudinal fold lines between the body portion and the side flaps thereof. From the scoring mechanism the blanks pass singly to a side flap gumming and folding mechanism of the kind illustrated and described in my pending application Serial No. 554,704, filed August 3, 1931, for Envelope machines. This mechanism includes a long, high speed conveyor comprising a pair of belts 22, which is disposed beneath a 10 relatively short opposed conveyor comprising a pair of belts 23. Rollers 24 carried by pivoted arms 25 rest by gravity upon the lower stretch of the conveyor 23 and serve to maintain the conveyors 22 and 23 in coacting relation throughout the active stretch of the latter. While the 15 blanks are under the influence of the two conveyors referred to, they pass a gumming mechanism 26 which applies gum to the lower face along the outer, longitudinal margin of the side flap 12. The gumming mechanism comprises a gum pot 27 and a roller 28 which runs therein and which stands substantially tangent to the plane of blank movement. A pendulously hanging block 29 of small mass stands in opposed 20 relation to the roller 28, but it does not present any surface which can under any circumstances contact the roller 28 because it has a channel formed in its lower face wider than the roller 28.

From the conveyor 23 the blanks pass to a side flap folding mechanism. This mechanism comprises upwardly inclined converging arms 29a which serve to turn the respective side flaps through approximately a quadrant. A pair of channel bars 30 overlie the belts of conveyor 22 and carry rollers 31 which ride upon the blanks and hold the blanks down against the conveyor 22. The channel bars 30 have forming plates 32 extending forward from the ends thereof and the folding of the side flaps is completed about these 35 forming plates by means of a belt folder 33. This folder comprises a pair of belts which act on the respective flaps, the active stretches of the belts being twisted from substantially upright to horizontal positions. At this operation the ungummed side flap is lapped over the gummed margin of the other side flap and adhesively united to it, provision being made of center seam pressing rollers 34 and 34a.

The rollers 34, 34a cooperate to feed the blanks singly to a gumming mechanism 35 which applies gum to the sealing flaps of the blanks. This gumming mechanism comprises a gum pot 36, a roller 37 running therein, a transfer roller 38, a cylinder 39, which carries a gumming bar 40, 40 and a cooperating bed roller 41. The blanks are transferred from the gumming mechanism by a feeding couple 42 onto a friction conveyor 43 which comprises a pair of endless belts 44 that run on pulleys 45 and 46. Between the belts 44 provision is made of a gripper conveyor 47 which comprises an endless chain 48 that runs on sprockets 49 and 50 in parallelism with the belts 44. Grippers 51 are provided at spaced intervals along the chain 48. The gripper construction is best illustrated in Figures 8 and 9. Each gripper includes a gripping jaw 52, a body portion 53 which is pivoted on a chain pin 54 and a tail piece 55 rigid with the jaw 52 and the body 53. A wire spring 56 is looped around a chain pin 57 and engages the tail piece 55 at one end, and the pin 54 at the other end, being stressed to urge the gripper in a counterclockwise direction, and hence to urge the jaw 52 toward closed position against the chain. A bar 58 extends beneath the upper stretch of the chain 48, guides

the latter, and serves by engagement with the tail pieces of the grippers to maintain the grippers open throughout a considerable portion of the travel thereof in the upper stretch of the chain. The friction conveyor 53 operates at a little higher speed than the gripper conveyor 47, and is therefore effective to cause the envelope blanks upon it to overtake the grippers, enter the jaws thereof, and be arrested by the body portions 53. Thus, every blank is accurately positioned as far forward in the associated gripper as it can go before the gripper is closed down upon it. Near the rear end of the conveyor 47 bar 58 slopes downward so that each gripper is permitted to close at this point. 15

The gripper carries the blank whose leading end it has seized around the sprocket 59, thereby inverting the blank and reversing the direction of travel thereof. The gummed sealing flap which was originally the upper trailing margin 20 is thus caused to become the lower trailing margin of the blank. A sprocket 59 around which the chain 48 runs is provided with a hub portion, 60 for engaging the tail pieces 55 of the grippers so that each gripper is caused to open and 25 release the blank held by it at a definitely predetermined point. This release is so timed that the blank is deposited gum face downward upon an endless drying conveyor 61 in position to have its trailing end gripped by one of a multiplicity 30 of grippers 62 carried by such conveyor.

Each of the grippers 62 consists of a finger rigid with one link of the conveyor chain 63. These grippers stand out tangentially to an end sprocket 64 on which the chain runs as they pass 35 around the sprocket, and hence are in an open position so that they may receive the deposited blanks. Each gripper, however, as soon as it reaches the straight stretch of the conveyor, comes down into contact with the chain and 40 grips the blank which has been deposited on it. The blanks are carried throughout the outgoing and return stretches of the drying conveyor 61 with their gummed faces toward the conveyor, and are discharged when the grippers again open 45 up on reaching the sprocket 64. In order to prevent release of the blanks when the conveyor chain 63 passes around sprocket 65 remote from the point at which the blanks are received and discharged, provision is made of a pair of bars 50 66 adapted to bend the fingers 62 inward and maintain them in gripping relation to the chain. Alternatively, the sprocket 65 may be made of such large diameter that it will not cause the grippers to open. 55

The conveyor as described has the important advantage that both the outgoing and return stretches are utilized. Other important advantages are also realized. An air chest 67 which is supplied with heated air under pressure is provided with openings or jets in the top and bottom thereof so that it constantly blows air against both stretches of the belt. This air chest, so situated, takes up no space which could be otherwise usefully employed and constitutes 60 a common means for supplying drying air to both stretches of the conveyor. This advantage is realized because of the fact that the blanks are delivered gummed face downward to the conveyor 61. 65

From the drying conveyor 61 the blanks are delivered to a short conveyor 68, three rolls 69, 70 and 71 cooperate with said conveyor, the roll 70 being fixed and the rolls 69 and 71 being adjustable. The roll 69 is made adjustable in order 75

to enable it to be set at a proper distance from the discharge point of conveyor 61 to properly receive blanks of varying lengths. The roll 71 is similarly adjusted toward and from a 5 cone device 72 which is provided for turning the blanks in the manner illustrated in Figure 11. The turning device 72 and a re-aligning mechanism 73 are of the same construction as the corresponding parts shown and described in my 10 pending application Serial No. 554,704, referred to above, and need not, therefore, be described in detail herein. From the latter of these devices the blanks advance side edge first instead of bottom end first. They are delivered to a feeding couple 74, thence to scoring means 15 and 15 to conveyors 76 and 77. The bottom flaps are gummed by gumming mechanism 18 and the bottom and sealing flaps are folded by sealing mechanism 19, both identical with the mechanism disclosed in Figures 4 and 5 of said pending application.

The completed envelopes are delivered onto a slow speed conveyor 80 and there accumulated.

I have illustrated and described in detail certain preferred embodiments of my invention. I 25 do not, however, wish to be confined to the embodiments shown, but what I desire to cover by Letters Patent is set forth in the appended claims.

30 I claim:

1. In an envelope machine, in combination, means for uniting the side flaps, means for then gumming and drying the sealing flap, means for thereafter turning the blank through 90°, means 35 for gumming the bottom flap, means for folding the bottom flap, and means for folding the sealing flap.

2. In an envelope machine, in combination, means for gumming, means for folding and 40 means for adhesively uniting the side flaps, means for then gumming the sealing flaps, an endless drying conveyor in the same vertical plane with said means to which the blanks are delivered, the conveyor being arranged to feed 45 the blanks throughout substantially the entire lengths of its outgoing and return stretches, and means for receiving the dried blanks and adhesively uniting the bottom flaps to the blank bodies, all of said instrumentalities being disposed substantially in a single vertical longitudinal plane.

3. In an envelope machine, in combination, means for gumming, means for folding and means for adhesively uniting the side flaps, means for then gumming the sealing flap, means for 5 drying the sealing flap, means for thereafter turning the blank through an angle of 90° in its own plane, means for then gumming the bottom flap, means for folding the bottom flap, and means for folding the sealing flap.

4. In an envelope machine, in combination, 10 means for gumming, means for folding and means for adhesively uniting the side flaps, means for then gumming the sealing flap, means for drying the sealing flap, means for thereafter turning the blank through ninety degrees, and 15 means for gumming the bottom flap, means for folding the bottom flap and means for folding the sealing flap.

5. The method of making an envelope which 20 consists in gumming, folding and adhesively uniting the side flaps, then gumming and drying the sealing flap, thereafter turning the blank through ninety degrees, then gumming the bottom flap, and then folding the bottom and sealing flaps.

6. In an envelope machine, the combination of 25 means for adhesively uniting two oppositely-disposed flaps, means for gumming a third flap, means for drying the third flap, means for thereafter turning the blank through ninety degrees, 30 means for gumming a fourth flap, means for folding said third flap and means for folding said fourth flap.

7. The method of making an envelope which 35 consists in interposing the steps of gumming and drying the sealing flap of the envelope and turning it through ninety degrees between the operation of folding the side flaps and the operation of folding the sealing flap.

8. The method of making an envelope which 40 consists in folding the side flaps, then gumming and drying the sealing flap, turning it through ninety degrees, then gumming the bottom flap, and then folding the bottom and sealing flaps.

9. The method of making an envelope which 45 consists in gumming, folding and adhesively uniting the side flaps, then turning it through ninety degrees, then gumming and drying the sealing flap, and gumming the bottom flap, and then folding the bottom and sealing flaps.
